UNITED STATES PATENT OFFICE.

JOHN RUTZ, OF BEACH, NORTH DAKOTA.

BINDER-HITCH.

979,709.

Specification of Letters Patent. Patented Dec. 27, 1910.

Application filed September 13, 1910. Serial No. 581,768.

To all whom it may concern:

Be it known that I, JOHN RUTZ, a citizen of the United States, residing at Beach, in the county of Billings and State of North Dakota, have invented a new and useful Binder-Hitch, of which the following is a specification.

This invention relates to binder hitches.

The object of the invention is, in a ready and practical manner simultaneously to operate two or more grain binders from one engine, and in such manner that one will not interfere with the other, whereby the time and labor incident to harvesting a field will be reduced to a minimum, and a pronounced saving in the cost of the procedure will be achieved.

With the above and other objects in view, as will appear as the nature of the invention is better understood, the same consists in the novel construction and combination of parts of a binder hitch, as will be hereinafter fully described and claimed.

In the accompanying drawing forming a part of this specification, and in which like characters of reference indicate corresponding parts: Figure 1 is a view in the nature of a diagram displaying the manner of connecting and positioning three grain binders. Fig. 2 is a top plan view of so much of the grain binder as is necessary to an understanding of the invention. Fig. 3 is a view in rear elevation of certain of the mechanism. Fig. 4 is a view in side elevation of another portion of the mechanism. Fig. 5 is an enlarged detail plan view of a portion of the mechanism shown in Fig. 2. Fig. 6 is a sectional detail view of a portion of the tongue operating mechanism. Fig. 7 is a transverse sectional view taken on the line 7—7 Fig. 5.

Referring to the drawings, 1 designates generally the frame of a grain binder which is supported upon the usual wheels not necessary to be shown. It may be stated at this point that as the cutting and binding mechanisms have nothing whatever to do with the present invention, they are omitted as their inclusion would obscure the parts that are employed in the structure and thus lead to confusion. It is also to be understood that the mechanism is duplicated on each binder; so that a description of one will serve for all. Arranged in front of the binder is a second frame embodying a beam 2 and a tongue rest 3 secured to the beam,

the frame being supported from the binder frame by a pair of bars 4 secured at their respective terminals to the binder frame and to a plate 5 rigid with the tongue rest. The beam 2 is also connected with one of the frame bars 6 of the binder frame by means of an extension 7 and a bolt 8.

Pivoted to the beam 2 is the binder tongue 9, of any preferred construction, and secured to the engine (not shown) in the usual manner. The tongue is caused to swing through a prescribed arc by means of a screw 10 that works in a swiveled nut 11 (Fig. 6) carried by the underside of the tongue. The screw connects through a universal joint 12 with a shaft 13 on which are keyed two bevel gears 14 and 15 the shaft being journaled in a bracket 16 bolted to the rest 3. The gears are designed to be engaged alternately or otherwise by a pinion 17 carried by the lower end of a shaft 18, the upper end of which is connected through a universal joint 19 with the lower end of a second shaft 20 the upper end of which is journaled in one of the rear frame bars of the binder frame and projects therethrough and carries a sprocket wheel 21 driven by the main sprocket chain 22 actuated by the movement of the machine in the usual manner. The lower end of the shaft 18 is journaled in a collar 23 loose on the shaft 13, thus to permit the pinion accurately to be brought into mesh with either of the gears 14 and 15. The shaft 18 extends through an orificed lug 24 carried by a plate 25 that works in a guide 26 provided with overhanging flanges 27, the guide 26 being supported by and rigid with the bracket 16. As shown in Fig. 5, the lug 24 is arranged to slide in the guide 26 and its two ends are engaged by two coiled springs 28 and 29 that bear against the inner walls of the bracket 16. These springs are so arranged as to maintain the pinion 17 normally out of engagement with the gears 14 and 15. To bring the pinion into mesh with either of these gears, there is a bell crank lever 30 provided which is pivoted upon the bracket 16, one arm of the lever being connected with the plate 25 and the other with a rod 31 that extends to and is connected with a shifting lever 32 arranged adjacent to the operator's seat 33, and being provided with usual spring latch 34 to interlock with a toothed segment 35 to hold the pinion in a shifted position. The

shaft 20 is driven in such direction that when the pinion is in mesh with the gear 15 the tongue 9 will move to the left, the reverse being true of the gear 14. In order to secure automatic ungearing of the pinion and gear with which it meshes when the tongue 9 has reached the limit of its swing in either direction, there is an automatic shifting means provided which comprises a rod 36 which passes through a lug 37 on the tongue and carries on each side thereof an adjustable stop collar 38. From this arrangement it will be seen that the instant the lug contacts with either of the collars, the rod will be shifted and thus unmesh the gear and pinion.

In order to connect one grain binder with another, each is provided with a reach bar 39 that extends rearward beyond the binder frame and connects with the tongue 40 of the next adjacent binder, this order being maintained throughout the series.

In operation, the operator of each of the binders determines the width of the cut to be made by the character of the grain. Thus for instance if the forward binder were running through very heavy grain, the operator of this machine would cut say only one half of the length of the knives, while the second and third binders might be running through lighter grain and would cut the full width of the knives.

It will be obvious that by the employment of the device of this invention that any number of binders may be employed in connection with one engine, their number being limited only by the power of the engine.

What is claimed is:

1. Means for swinging the tongue of a binder to change its line of travel, comprising a screw operatively connected with the tongue, reversing gears to transmit motion to the screw, a pinion driven from the main drive chain, and means for shifting the pinion as required.

2. Means for swinging the tongue of a binder to change its line of travel, comprising a screw operatively connected with the tongue, reversing gears arranged to transmit motion to the screw, a pinion driven from the main drive chain of the machine to actuate either of the gears, means for shifting the pinion as required, from the operator's seat, and automatic means for shifting the pinion at the limit of the swing of the shaft in either direction.

3. Means for swinging the tongue of a

binder to change its line of travel, comprising a screw operatively connected with the tongue, reversing gears arranged to transmit motion to the screw, a pinion driven from the main drive chain to actuate either of the gears, manual means for shifting the pinion as required, automatically operating means to shift the pinion at the limit of the swing of the tongue in either direction, and means for centering the pinion relative to the reversing gears.

4. Means for swinging the tongue of a binder to change its line of travel, comprising a screw, a swiveled nut carried by the tongue and with which the screw engages, a train of reversing gears, a shaft including a universal joint connecting with the screw, a pinion interposed between the gears, a shaft carrying the pinion and driven from the main operating chain of the machine, a guide in which the latter shaft is supported, means for shifting the guide to bring the pinion into mesh with either of the gears, a lug carried by the tongue, a rod secured to the guide and passing through the lug, and collars carried by the rod and arranged to contact with the lug whereby to shift the tongue automatically at the limit of the swing in either direction.

5. Means for swinging the tongue of a binder to change its line of travel, comprising a screw, a swiveled nut carried by the tongue and with which the screw engages, a train of reversing gears, a shaft including a universal joint, connecting with the screw, a pinion interposed between the gears, a shaft carrying the pinion and driven from the main operating chain of the machine, a guide in which the latter shaft is supported, means for shifting the guide to bring the pinion into mesh with either of the gears, a lug carried by the tongue, a rod secured to the guide and passing through the lug, collars carried by the rod and arranged to contact with the lug whereby to shift the tongue automatically at the limit of the swing in either direction, and resilient means for centering the pinion relative to the reversing gears.

In testimony that I claim the foregoing as my own, I have hereto affixed my signature in the presence of two witnesses.

JOHN RUTZ.
